(57) **CLAIM**

The ornamental design for a play structure for brooder, as shown and described.

DESCRIPTION

FIG. 1 is a perspective view of a play structure for brooder showing my new design;

FIG. 2 is another perspective view thereof;

FIG. 3 is another perspective view thereof;

FIG. 4 is a front elevational view thereof, the rear elevational view being a mirror view thereof;

FIG. 5 is a right side elevational view thereof, the left side elevational view being a mirror view thereof;

FIG. 6 is a top plan view thereof, the bottom view being a mirror view thereof;

FIG. 7 is a perspective view shown in an alternate configuration;

FIG. 8 is a front elevational view thereof, the rear elevational view being a mirror view thereof;

FIG. 9 is a top plan view thereof, the bottom view being a mirror view thereof;

FIG. 10 is an enlarged perspective view of detail 10-10 in FIG. 2;

FIG. 11 is an enlarged perspective view of detail 11-11 in FIG. 10;

FIG. 12 is an enlarged perspective view of detail 12-12 in FIG. 11; and,

FIG. 13 is an enlarged perspective view of detail 13-13 in FIG. 11.

Dash lines of short dashes that represent portions of the article show those portions of the article in positional states other than as shown in solid line. Other dash lines of short dashes represent arrows indicative of relative movement and form no part of the claimed design. The heavy dash lines of a repeating short-dash, short-dash then long-dash represent section cut lines or enlarged scale detail bounds lines and form no part of the claimed design. All other broken lines in the drawing represent environmental subject matter that forms no part of the claimed design.
